RADIATOR FLUSHING VALVE

Charles S. Davis, Pittsburgh, Pa.

Application April 7, 1932, Serial No. 603,716

1 Claim. (Cl. 123—170)

This invention relates to improvements in radiator flushing and cleansing devices and it is among the objects thereof to provide a valve connection in the radiator hose line which shall be permanent and which shall be provided with means for attaching a standard coupling or a water hose whereby the full force of a water pressure supply system may be made use of in loosening and removing sediment accumulating 10 in the relatively thin tubes of a radiator core.

Another object of the invention is the provision of a valve arrangement whereby water under pressure may be selectively circulated through a radiator by the application of pressure to the bottom thereof or through the cooling jacket of an engine and thence out at the top of the radiator without causing the flush-out water in the cooling jacket to circulate through the radiator tubes.

Another object of the invention is the provision of a special valve having a removable element whereby it is rendered unobstructive to the normal flow of the cooling medium in a radiator and water jacket system when not in use, 25 and which shall be readily convertible to a controllable valve element for directing the application of flushing fluid when it is desirable or necessary to cleanse the circulating system.

Various forms of radiator flushing methods 30 have been heretofore proposed but none of them provide for the circulation of a flushing fluid through the tubes of the radiator core in one direction only, and for this reason such methods are not only deficient but sometimes aggravate 35 the clogged condition of the tubes. The prior methods do not recognize the fact that pieces of rubber tubing and other relatively large particles suspended in the cooling fluid such as rust or scale from the cooling jacket become lodged 40 in the radiator tubes to firmly adhere or wedge therein by virtue of the direction of flow of the fluid through the core structure.

In automobiles, the water in the cooling system is commonly circulated by providing a water 45 pump at the hose connection near the bottom of the radiator to draw the water downwardly through the radiator tubes and deliver it to the cooling jacket of the engine from which it recirculates through a flexible hose connection at the top of the radiator and again passes downwardly through the tubes. Continuous circulation in one direction only will cause a wedging 50 and adherence of the foreign particles in the tubing which ultimately clog the flow passages

resulting in inefficient circulation and consequent over-heating of the engine.

The present invention is designed to simplify the flushing of radiator core structures by providing an attachment for a water line as a permanent part of the circulating system, such a device being designed to permit directing the flushing fluid either in the reverse direction of normal flow, namely, through the bottom of the radiator core upwardly and thence permitting it 60 to escape at the top of the radiator or direction may be reversed to establish flow through the cooling jacket thence from the water jacket out through the top of the radiator without permitting the flushing fluid to circulate through the 70 radiator tubes. In this manner, any foreign particles in the radiator core are dislodged and flushed out at the top of the radiator and any sludge or loose scale in the cooling jacket is 75 expelled from the top of the radiator without passing through the tubes of the core.

In the accompanying drawing constituting a part hereof in which like reference characters designate like parts,

Figure 1 is a side elevational view of an automobile engine and radiator structure illustrating an embodiment of this invention;

Figure 2 vertical cross-sectional view of a special form of valve employed in practicing the invention;

Figure 3 a top plan view of the valve;

Figure 4 cross-section taken along the lines IV—IV, Figure 2;

Figure 5 a top plan view of a closure cap; and,

Figure 6, a side elevational view of the cap 90 shown in Figure 5.

With reference to the several figures of the drawing, the reference character 1 designates an automobile engine having connections through flexible conduits 2 and 3 with the top and bottom 95 respectively of a radiator 4.

The radiator is provided with the usual cap 5 which covers the opening through which water is supplied to the radiator, and the conduits 2 and 3 are connected to the cooling jacket of the engine 1 in the conventional manner.

Interposed between the connections of the radiator and cooling jacket of the lower conduit 3 is a valve 6 of the construction shown in Figure 2 having a through passage 7 Figure 2, having 105 connections at 8 with tube 3 and a connection at 9 with the passage of the cooling jacket of the engine.

Disposed within the casing of valve 6 is a sleeve 10 having a plurality of openings 11, there being 110

three such openings as shown in Figure 4 at right angles to each other.

The top of the valve is provided with a hexagonal or octagonal shoulder 12 for receiving a wrench 13, Figure 1, and the top of the valve is threaded at 14 to receive the coupling 15 of a water hose 16 which may be the conventional form of garden hose. The sleeve 10 is provided with a shoulder 17 which is adapted to seat on the top of valve casing 6 and to be engaged by a flange ring nut 18 that interacts with the threads 19 provided on the exterior of the valve casing.

When the valve 6 is not in use the ring nut 18 may be removed and valve sleeve 10 lifted bodily from the valve casing. Instead of replacing the ring nut 18, a cap or closure 20, Figures 5 and 6, may be screwed on the threads 19 of the valve casing to seal the top of the valve and in this condition the passage 7 of the valve is substantially of the same diameter or area as the remaining passage of the circulating system thus providing an unobstructed path to the flow of the cooling liquid in the cooling system.

The operation of the flushing system is briefly as follows: Assuming valve sleeves 10 to be assembled in the casing 6 in the manner shown in Figure 2, and a hose 16 coupled to the thread 14 as shown in Figure 1 the handle member 13 is turned to the position which brings one of the openings 11 in alignment with the connection leading to the bottom of the radiator core. The radiator cap 5 is then removed and water pressure is turned on hose 16 which causes the pressure fluid to pass to valve sleeve 10 and then through the connection 8 into the bottom of the radiator from which it passes upwardly through the tubes of the core structure flushing out at the opening at the top thereof. By connecting the water hose 16 in this manner, the total pressure of the water supply source is available to dislodge any accumulations in the tubing thereby thoroughly cleansing the core structure.

The valve handle 13 is then moved to the position where the port 11 of valve sleeve 10 is opened to the connection 9 while the body of the valve sleeve 10 shuts off the connection to passage 8. This can be done without disconnecting the water supply at the hose 16, and the water under pressure will then pass through the water jacket of engine 1 and pass outwardly through the hose connection 2 to the top of the radiator and through the top opening.

Since the tubes of the radiator core structure are filled with water when circulation is effected through the cooling jacket water will not pass downwardly through the tubing and the foreign matter from the jacket will flush out at the top of the radiator. Similarly, when the water is flushed through the core structure by passing it upwardly through the tubing to escape at the top of the radiator, it will not pass through the cooling jacket of the engine but will freely flush out through the top opening of the radiator structure.

After both the radiator and cooling jacket have been flushed as explained, handle 13 may be set to connect the pressure source with both connections 8 and 9 to simultaneously flush the radi-

ator and jacket to remove any solid particles still remaining.

It is, of course, evident that instead of the water hose 16, a steam line or compressed air connection may be connected with valve 6, and steam or air under pressure may be applied in the same direction and in the same manner as explained in connection with the application of the flushing fluid.

After the radiator and cooling jacket have been thoroughly flushed, the valve sleeve 10 may be removed by removing ring nut 18, and replacing the latter with the closure cap 20 to seal the valve, thus affording an unobstructed passage of the circulating fluid in the conventional manner.

Although removal of the valve 10 is suggested, it is not at all necessary since the ports 11 of valve sleeve 10 can be made precisely of the same area as the area of the conduit or passages through which the cooling fluid normally passes and the valve sleeve retaining member 18 may be packed or otherwise sealed against leakage when the valve sleeve is permanently retained in the valve casing.

It is evident from the foregoing description of the invention that by installing a valve of the character herein described as a permanent element in a circulating system particularly in the bottom connection of the radiator, with means for directing the flushing fluid in either the direction of the radiator or the cooling jacket, that the radiator tubes can be efficiently cleaned without the inconvenience of dismembering any of the connections of either the radiator or the engine, and because of this accessibility of the flushing element, it is apparent that they will be employed with sufficient frequency to maintain the circulating system in proper condition.

Although one embodiment of the invention has been herein illustrated and described, it will be obvious to those skilled in the art that various modifications may be made in the details of construction without departing from the principles herein set forth.

I claim as my invention:

In a water cooling system for internal combustion engines the combination of a cooling jacket surrounding the engine cylinders, a radiator having a conduit connection at the bottom with the lower part of the cooling jacket and a conduit connection at the top with the upper part of said jacket to constitute a circulating system, means in said system for normally circulating water through the radiator and from the bottom of the radiator through the cooling jacket to the top of the radiator and adjustable means in said system operable in one position for directing a flushing fluid from the bottom of the cooling jacket to the top of the radiator while shutting off flow through said radiator and operable in another position for directing the flushing fluid from the bottom of the radiator to the top thereof while shutting off flow through the cooling jacket, said means being operative without breaking the radiator and cooling jacket conduit connections.

CHARLES S. DAVIS.
